ATTORNEYS

UNITED STATES PATENT OFFICE.

JOHN E. JOHNSON, OF HAYFIELD, IOWA.

DESIGN FOR A BADGE.

No. 39,336.

Specification for Design.

Patented June 9, 1908.

Application filed April 7, 1908. Serial No. 425,793. Term of patent 3½ years.

To all whom it may concern:

Be it known that I, JOHN E. JOHNSON, a citizen of the United States, and a resident of Hayfield, in the county of Hancock and State of Iowa, have invented a new, original, and ornamental Design for a Badge, of which the following is a specification, reference being had to the accompanying drawing, forming part thereof.

The figure is a front view of a badge showing my new design.

I claim:

The ornamental design for a badge as shown.

JOHN E. JOHNSON.

Witnesses:

AUGUST LOOCK,
R. E. HAPKE.
